SAMUEL SEGAL.
PADLOCK.
FILED SEPT. 14, 1921.

UNITED STATES PATENT OFFICE.

SAMUEL SEGAL, OF NEW YORK, N. Y., ASSIGNOR TO SEGAL METAL PRODUCTS COMPANY INC., OF NEW YORK, N. Y., A CORPORATION OF DELAWARE.

PADLOCK.

Application filed September 14, 1921. Serial No. 500,607.

To all whom it may concern:

Be it known that I, SAMUEL SEGAL, a citizen of the United States, and a resident of New York, in the county of New York and 5 State of New York, have invented certain new and useful Improvements in Padlocks, of which the following is a specification.

My invention relates to padlocks and has for its object the production of a padlock 10 of strength and of simplicity of construction.

A further object of the invention is the production of a padlock of the above character having locking means adapted to interlock with the legs of the shackle and adapted 15 to be actuated by a pin tumbler mechanism, the key plug of said mechanism being prevented from forward withdrawal through the padlock by said locking means. 20 A further object of the invention is the production of a padlock having a shackle one leg of which may be entirely withdrawn from the padlock while the other leg of the shackle may normally not be withdrawn and 25 means permitting both legs to be withdrawn when desired whereby a new shackle may be substituted.

A further object of the invention is the production of a padlock provided with locking means actuated by the key plug of a pin tumbler mechanism.

A still further object of the invention is the production of a padlock provided with locking means adapted to interlock with both 35 sides of both legs of the shackle.

Still other and further objects and advantages of the invention are the provision of a padlock in which the casing thereof acts as a stop to limit the movement of the 40 shackle locking means, the provision of means in the padlock acting to retain the shackle locking means in locked position and to retain the key plug in proper position for insertion of the key, and the provision of a padlock having a novel construction permitting the interior mechanism thereof to be 45 slipped as a unit and in operative position into the casing.

The invention consists in the novel parts 50 and combinations thereof hereinafter more particularly described and then specified in the claims.

In the accompanying drawing showing a practical embodiment of the invention:

55 Fig. 1 is a side elevation of the padlock

with the hollow body or casing thereof in section.

Fig. 2 is a horizontal section on the line 2—2 of Fig. 1.

Fig. 3 is a horizontal section on the line 3—3 of Fig. 2.

Fig. 4 is a horizontal section on the line 4—4 of Fig. 1.

Fig. 5 is a horizontal section on the line 5—5 of Fig. 1.

Fig. 6 is a side elevation of the padlock showing one leg of the shackle withdrawn.

Fig. 7 is a view similar to Fig. 4 showing the locking means for the shackle in inoperative position.

Referring to the several figures of the drawing:

1 indicates the hollow body or casing of the padlock provided with bores or annular openings in the top or upper wall 2 thereof 75 for receiving the long and short legs 3 and 4 respectively of a shackle 5. 6 indicates the plug portion of the padlock which, together with all the other interior mechanism to be presently described, is adapted to be 80 slipped as a unit within the casing 1. Said plug portion is provided with a face plate 7 which is adapted to engage the lower edge of the casing when the parts are assembled. Said plug portion 6 is held and locked in 85 proper position within the casing by means of bolts 7' passing therethrough and through the casing with the ends thereof riveted to the casing. The portion 6 is also provided on one side with a bore 8 for reception of 90 the longer leg 3 of the shackle and with an annular opening 9 on the other side for receiving the shorter leg 4. The portion 6 constitutes the barrel of an ordinary pin tumbler lock and receives therein a rotatable 95

key plug 10 the head 11 of which is received by a suitable annular opening in the face plate 7. 12 indicates a plurality of spring-actuated tumblers slidably mounted in suitable chambers in the plug portion 6 100 and adapted to enter suitable openings (not shown) in the key plug 10 to prevent rotation thereof. The key plug 10 may be rotated by a suitable key inserted in a slot (not shown) therein to force the pin 105 tumblers 12 from within the openings within the key plug in a manner well known and forming no part of my invention. The inner end of said key plug 10 is provided with slots 13 on opposite sides thereof forming 110

ing a shoulder 14 on the end of said key plug.

15 indicates locking plates removably fitting within suitable horizontal slots adjacent the top of the plug portion 6 of the padlock, said plates being provided with squared lugs 16 slidably interfitting with transverse slots 17 in the top of said plug portion. The plates 15 engage or fit within 10 the slots 13 and at all times engage the shoulder 14 on said key plug whereby a forward withdrawal of said key plug from the portion 6 is effectively precluded. The long and short legs 3 and 4 respectively on 15 the shackle 5 are also provided with horizontal slots 18 on either side of both legs which slots are in horizontal alignment with the slots 13 adjacent the end of the key plug when said legs are inserted within the bore 8 and opening 9, whereby the ends of the locking plates 15 will engage said slots 18 in the legs of the shackle to interlock therewith and to prevent removal of the shackle 20 from the body or casing of the padlock. 25 The plates are held in interlocked engagement with the legs by means of a spring 19 the arms of which engage and press said plates inwardly or towards each other. It will be noted also that one of the arms of 30 the spring is shorter than the other arm, that one arm engages one of the plates adjacent one end of one of the slots 13 while the other arm engages the other of said plates adjacent the opposite end of the other of said 35 slots 13. The pressure as thus applied by the arms of the springs tends to rotate said key plug in a direction whereby said plug will be retained in proper position for the insertion of a key therein without the necessity of "feeling" to find the key-slot therein. 40 Upon rotation of the key plug 10 by a suitable key the locking plates 15 are forced or spread outwardly against the action of the spring 19, the outward movement of said 45 plates being limited by the side walls of the casing 1 which act as stops therefor. This movement frees the ends of the locking plates from their engagement with the slots 18 of the legs of the shackle and but a partial 50 rotation, approximating a one-sixth of a revolution, of the key plug is possible or necessary to effect the desired results. The shackle may then be withdrawn from the padlock body in an obvious manner and 55 when the key is released the locking plates are immediately forced back by the spring 19 into closed or locking position. When the key plug is rotated and the plates are forced outwardly against the action of the 60 spring 19 or are permitted to move inwardly by the action of said spring, the lugs 16 which slidably interfit with the transverse slots 17, as has been described, prevent dislodgment of said plates from their proper 65 positions.

The longer leg 3 of the shackle is provided with a reduced portion or shank 20 and a headed end 21 slidably interfitting with the bore 8 and the lower edge of which is bevelled inwardly. The said shank is hollowed 70 out to receive a compression spring 22 which engages the bottom of the bore 8 and tends by its action to force the leg 3 upwardly within the bore. 23 indicates a bar comprising a detent fitting within a suitable slot in 75 the side of the portion 6 with its back edge engaging an inner side wall of the casing (Fig. 5). One end of said detent terminates in an arm 24 which is normally in vertical alignment with the opening 9 while the other end is hooked or curved as at 25. Said hooked end is provided with a pin 26 carrying a spring 27 which engages a shoulder 28 on the plug portion 6. The detent 23 is 80 slidably horizontally and the action of the 85 spring 27 tends to retain the hooked or curved portion 25 in engagement with the shank 20.

When the legs of the shackle are in interlocked engagement with the locking plates 90 16 and it is desired to unlock the parts the key plug 10 is rotated to spread the locking plates outwardly in the manner previously described. The short leg 4 of the shackle will then be projected from the body or casing by the action of spring 22 and the shackle may be swivelled around on its longer leg as shown in Fig. 6 although complete withdrawal of the long leg is normally not possible due to the engagement of the hooked or curved end 25 of the detent 23 with the head 21 of the long leg 3. Complete withdrawal of the leg is possible, however, by insertion of a key or other suitable instrument through the opening 9 and into engagement with the side of the arm 24 of the detent and a movement of the detent laterally by pressure thereagainst and against the action of the spring 27 to permit the curved end 25 to clear 100 or become released from its engagement with the head 21 of the long leg 3. When a new or the old shackle is inserted in position, the end of the shorter leg being also bevelled as illustrated, the bevelled ends of the legs will spread the locking plates apart against the action of the spring 19 and the locking plates will automatically interlock with the slots 18 by a snap action when they are in alignment therewith. It will be noted also that the lower bevelled end of the long leg 3 will 110 strike against the curved end 25 of the detent, forcing said detent laterally momentarily against the action of the spring 22 and until the head 21 has cleared said curved end 25 whereupon the long leg may not be completely withdrawn from the body or casing until the detent has again been manipulated 115 in the manner previously described.

What I claim as my invention is:—

1. In a padlock, a body, a shackle, locking 130

means for said shackle, a key plug mounted in said body and adapted to actuate said locking means and a shoulder on said key plug adapted to be engaged by said locking means to prevent removal of said key plug from said body.

2. In a padlock, a body, a shackle, a key plug mounted in said body and provided with a slot therein and locking means adapted to prevent removal of said key plug from said body by engagement with said slot and being also adapted to interlock with said shackle.

3. In a padlock, a body, a shackle and locking means within said body adapted to interlock with opposite sides of each of the legs of said shackle.

4. In a padlock, a body, a shackle having a slot in opposite sides of each of the legs thereof and locking means within said body adapted to interlock with all of said slots.

5. In a padlock, a body, a shackle, a key plug mounted in said body and provided with a slot therein and locking means engaging said slot and adapted to interlock with said shackle.

6. In a padlock, a body, a shackle and locking means within said body adapted to interlock with said shackle, said body acting as a stop to limit the movement of said locking means.

7. In a padlock, a body, a shackle, a key plug mounted in said body, locking means engaging said key plug and adapted to interlock with said shackle and means tending to retain said locking means in interlocked position.

8. In a padlock, a body, a shackle, a key plug mounted in said body, locking means adapted to interlock with said shackle and means tending to retain said locking means in interlocked position and tending to rotate said key plug.

9. In a padlock, a body, a shackle, a key plug mounted in said body, locking means engaging said key plug and adapted to interlock with said shackle and means tending to retain said locking means in interlocked position and tending to rotate said key plug.

10. In a padlock, a body, a shackle, a key plug mounted in said body, a locking plate engaging said key plug and adapted to interlock with said shackle and to be actuated by said key plug.

11. In a padlock, a body, a shackle, a plug portion within said body provided with a horizontal and transverse slot therein, a locking plate mounted in said horizontal slot and adapted to interlock with said shackle and a lug on said locking plate entering said transverse slot.

12. In a padlock, a body, a shackle, a key

plug mounted in said body and locking means adapted to interlock with said shackle and to be spread outwardly by said key plug. 65

13. In a padlock, a body, a shackle, a key plug mounted in said body, locking means adapted to interlock with said shackle and to be spread outwardly upon rotation of said key plug and means tending to retain said locking means in interlocked position. 70

14. In a padlock, a body, a shackle having legs adapted to enter said body, locking means for interlocking with the legs of said shackle and means normally acting to prevent the removal of one of said legs from said body and adapted to be actuated to permit such removal. 75

15. In a padlock, a body, a shackle having legs adapted to enter said body, locking means for interlocking with the legs of said shackle and a detent normally engaging one of the legs of said shackle to prevent removal of said leg from said body and adapted to be actuated to permit the removal of 85 said leg.

16. In a padlock, a body, a shackle having legs adapted to enter said body, locking means for interlocking with the legs of said shackle, a detent normally engaging one of the legs of said shackle to prevent removal of said leg from said body and adapted to be actuated to permit the removal of said leg and means tending to retain said detent in engagement with said leg. 95

17. In a padlock, a body, a shackle having legs adapted to enter said body, means within said body adapted to interlock with said legs, a detent normally engaging one of the legs of said shackle to prevent removal of said leg from said body and adapted to be actuated to permit the removal of said leg and a spring engaging said detent and tending to retain said detent in engagement with said leg. 100

18. In a padlock, a body provided with openings therein, a shackle having legs adapted to be inserted through said openings, means within said body adapted to interlock with said legs, and a detent normally engaging one of said legs to prevent withdrawal of said leg from said body, said detent being accessible through one of the openings in said body whereby it may be actuated to release it from engagement with 110 said one leg and permit said leg to be withdrawn from said body. 115

Signed at New York, in the county of New York and State of New York, this 7th day of September, A. D. 1921.

SAMUEL SEGAL.
